UNITED STATES PATENT OFFICE.

EDWIN POLLARD, OF SILSDEN, ENGLAND.

DESIGN FOR A FIRE-KINDLER.

SPECIFICATION forming part of Design No. 34,981, dated August 20, 1901.

Application filed May 18, 1901. Serial No. 60,939. Term of patent 14 years.

To all whom it may concern:

Be it known that I, EDWIN POLLARD, a subject of the King of Great Britain, residing at Silsden, Yorkshire, England, have invented and produced a new and original Design for Fire-Kindlers, of which the following is a specification, reference being had to the accompanying drawings, forming a part thereof.

In the drawings, Figure 1 shows a view of one face of a kindler embodying my design. Fig. 2 is a view of the opposite face. Fig. 3 is an edge view of one side. Fig. 4 is an end view.

The kindler-block has for its leading feature grooves cut into opposite faces, these grooves being of equal width, but running in different directions. The grooves on one face run straight with the sides of the block and parallel to each other, while the grooves upon the other face run at an angle to the sides of the block and across the line of the straight grooves. As the grooves upon the two faces are of a combined depth exceeding the thickness of the block, openings are formed where

they cross, and these openings are diamond-shaped. The ribs or projections formed between the grooves are of uniform width. The straight grooves are shown at *a* with the intermediate ribs *b*, while the inclined grooves are shown at *c* and the intermediate ribs at *d*. In the side view of Fig. 3 is shown the plain face of the outside rib *b*, and forming a continuation of this side are the ends of the inclined ribs *d*, these ribs being separated by the spaces *c* between. In the end view the square ends of the ribs *b* are shown with the grooves *a*, while below the series of ribs *b* are seen the ends of the inclined ribs *d*, forming a continuation of and integral with the ribs *b*, portions of the ends of the inclined ribs overlapping and crossing the grooves *a*.

What I claim is—

The design for a kindling-block as shown and described.

EDWIN POLLARD.
